UNITED STATES PATENT OFFICE.

JULIUS SIKES, OF CHICAGO, ILLINOIS.

FIREARM.

1,089,086.

Specification of Letters Patent.

Patented Mar. 3, 1914.

Application filed August 16, 1912. Serial No. 715,361.

To all whom it may concern:

Be it known that I, JULIUS SIKES, a citizen of the United States, and a resident of Chicago, in the county of Cook and State 5 of Illinois, have invented certain new and useful Improvements in Firearms; and I do hereby declare that the following is a full, clear, and exact description thereof, reference being had to the accompanying 10 drawings, and to the letters of reference marked thereon, which form a part of this specification.

This invention relates to that class of firearms adapted to be forced into and through 15 an embankment or earthworks so as to form an aperture in the embankment and to be aimed or sighted and discharged while in the aperture thus formed.

The principal object of the invention is 20 to provide a firearm having a barrel and a hollow tube adapted to be removably mounted upon and to extend longitudinally of the barrel and having front and rear sights so arranged with respect to the hollow tube as to be in alinement with the opening 25 through the tube and visible to one sighting through the tube and removable plugs for closing the forward end of the tube and barrel, all so constructed as to enable 30 the barrel and tube to be repeatedly forced into or through an embankment or earthworks in such a manner as to form a tunnel or aperture in the earth adapted to enable the firearm to be aimed or sighted 35 and discharged while in the tunnel or opening thus formed and to prevent the earth from falling in upon the barrel and obscuring the sights, whereby the person using the 40 firearm is enabled to be shielded and protected by the embankment through which the barrel and tube are thus inserted.

Other and further objects of the invention will appear from an examination of the accompanying drawings and from the following description and claims.

The invention consists in the features, combinations, and details of construction herein described and claimed.

In the accompanying drawings, Figure 1 50 is a view in side elevation of a firearm constructed in accordance with my invention and provided with my improvements; Fig. 2, a view in side elevation of a portion of a firearm provided with a hollow tube 55 mounted upon the barrel and with sights extending above the level of the bottom of

the aperture formed by the tube, with parts of the tube and barrel broken away to show the arrangement of the forward sight and the connected removable plugs; Fig. 3, a detail view in vertical section of the muzzle of a firearm constructed in accordance with my improvements and provided with a hollow tube and a forward sight extending into the latter, and separate removable 65 plugs for the front end of the barrel and tube, respectively; Fig. 4, a view in side elevation of a firearm constructed in accordance with my improvements and showing the same extending through an embankment or earthworks in position to be aimed and discharged while in the aperture or tunnel formed by forcing the muzzle of the firearm through the embankment; Fig. 5, a detail view of a ramrod for removing the 70 plugs from the tube or tube and barrel; Fig. 6, a view in side elevation of a firearm provided with a hollow tube formed of a plurality of telescoping sections removably secured to the top of the barrel and having 75 front and rear sights in position to be visible through and in alinement with the center of the tube; and Fig. 7, a detail view in longitudinal section of the tube shown in Fig. 6, with a portion broken away. 85

In constructing a firearm in accordance with my invention and provided with my improvements, I provide a gun which may be in the form of an ordinary rifle or cannon, and which, in the form shown in the 90 drawings, comprises a stock A, a lock B, a barrel 10, a front sight 15, and a rear sight 19.

A hollow metal tube 11 is provided having an aperture 14 in its bottom side at or 95 near the front end of the tube, adapted to admit the front sight 15 which extends, preferably, through the bottom wall of the tube, and into the interior of the tube or of the longitudinal aperture formed by the 100 tube, in position to be visible to one sighting through the tube or taking aim. This tube is removably secured to the top of the barrel by means of metallic bands 12, or by any desired similar, ordinary or well known 105 means for removably securing the same firmly in position upon the barrel.

Plugs 16 and 17 which may be connected by an outer connecting body portion 18, as shown in Fig. 2, are provided. These plugs 110 are adapted to close the muzzle or forward end of the barrel and the forward end of

the tube and to remain in position during the operation of forcing the barrel and tube through an embankment or earthworks preparatory to sighting and discharging the 5 weapon while in the aperture or tunnel thus formed by means of the weapon to be fired.

The hollow tube is in the same vertical plane with the front and rear sights and, of course, in the same vertical plane with 10 the center of the barrel. The front sight is, preferably, inclosed within the tube and entirely covered thereby, while the rear sight may be on the outside of the rear end of the tube but adjacent to the latter; and 15 both sights are in such position that they are in alinement with the axial center of the tube and of the aperture formed by the tube, and both sights extend above the level of the bottom of said aperture, and are both 20 visible or in the line of vision of one sighting through the tube.

It is very desirable to provide a tube which is rigid transversely but adapted to be collapsed longitudinally into as compact a 25 form as possible and to be extended and secured upon the barrel of a firearm with facility. In order to accomplish this the tube may be made in the form of a plurality of telescoping sections 21, as shown in Figs. 6 30 and 7, the section at the forward end or muzzle of the gun being provided with an opening 14 for admitting the front sight, as already suggested, and the tube tapered and so arranged that its relatively small end is 35 in the direction of the muzzle of the firearm and its relatively large end in the direction of the breech or stock and adjacent to the rear sight, the front and rear sights being each so constructed and arranged as to extend 40 above the level of the bottom of the tube and in the same vertical plane as the axial center of the tube and in the line of vision of one sighting through the latter, as already suggested. The telescoping tube 45 thus provided is adapted to be secured to the firearm by means of metallic bands 12, as already described in connection with the form of the tube shown in Fig. 1.

The plugs for closing the forward ends 50 of the tube and barrel, respectively, may be separate, as shown in Fig. 3, in which the plug 17 serves to close the muzzle of the firearm and is adapted to be removed by the discharge of the latter, and the plug 26 55 serves to close the forward end of the tube and is adapted to be removed by means of the ramrod 20, shown in Fig. 5, and which may be provided with an enlarged end portion 27, as shown in said figure.

60 A firearm provided with a barrel, tube and sights, constructed and arranged as above described, is adapted to be forced through an embankment or earthworks in such a manner as to form an aperture or tunnel 65 through such embankment, and to form a

casing or non-collapsible wall for such aperture or tunnel adapted to shield the sights and prevent the sights from becoming obscured by reason of the earth or other material falling in upon the barrel or from other causes, and by thus enabling the firearm to be inserted at a proper distance below the level of the top of the embankment and at any desired point and to be repeatedly removed and inserted in different positions 70 in such a manner as to enable the firearm to be sighted and fired while in the opening thus formed by forcing the muzzle or barrel and tube through the embankment, the user is enabled to insert, aim and discharge the 75 weapon repeatedly from different positions and to be entirely protected by the embankment while so employing the weapon.

The tube is adapted to be removed with facility and to be collapsed into as compact a form as possible so as to be readily carried from place to place as required, and so as to be readily available when required for the uses and purposes above set forth, and the aperture in the embankment formed by thus 80 forcing the firearm therethrough is practically entirely closed by the weapon, and yet the earth may be sufficiently loose to enable the firearm to be moved or adjusted so as to point in the desired direction and to enable the sights to be visible and a proper aim obtained with the gun in any desired adjusted position and the user in position to be 85 entirely shielded by the earthworks or embankment.

I claim—

1. A firearm comprising in its construction a barrel, a tube mounted on and extending longitudinally of the barrel and normally open at both ends, a front sight extending inside of the tube, a rear sight adjacent to the rear end of the tube, the tops of both sights being above the level of the bottom of and in alinement with the hollow portion of the tube, and a plug adapted to be removably mounted in the front end of the tube, the tube, sights and plug being so constructed and arranged as to enable the barrel and tube to be forced through an embankment of earth and the plug removed by 105 means of a rod inserted from the rear of and through said tube, and the firearm sighted and discharged while extending through the 110 embankment.

2. A firearm comprising in its construction a barrel, front and rear sights therefor, a hollow tube adapted to be removably attached to the barrel of the firearm with its open rear end adjacent to the rear sight, said tube having an aperture in the bottom of 125 and adjacent to the front end thereof adapted to admit the top of the front sight to the interior of said tube, a plug adapted to be removably mounted in the front end of the barrel, and a plug adapted to be removably 130

mounted within the front end of the tube and adapted to prevent the same from being clogged when the rifle is forced through an embankment of earth or similar substance 5 and means for removing the plug in said tube.

3. A firearm comprising in its construction a barrel, front and rear sights therefor, and a hollow tube extending over the front 10 sight and comprising a plurality of telescoping sections removably attached to the barrel in position to extend longitudinally of the barrel between the front and rear sights, and provided with a normally unob- 15 structed longitudinal opening having its

axial center in the same vertical plane in which the sights are located, the tops of the sights being above the level of the bottom of said longitudinal opening and a plug adapted to be removably mounted in the 20 front end of said tube.

In testimony, that I claim the foregoing as my invention I affix my signature in the presence of two witnesses, this 12th day of August A. D. 1912.

JULIUS SIKES.
